CLAIM

The ornamental design for a two-part hanging tray for open beverages, as shown and described.

DESCRIPTION

FIG. 1 is a front upper perspective view of a hanging tray showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front upper exploded perspective view thereof;

FIG. 9 is a lower front exploded perspective view thereof;

and,

FIG. 10 is a rear upper perspective view thereof.

My hanging tray for open beverages is characterized by an extension arm that curves out and above the region where one or more beverages would rest.
